US0D1000915S

(12) **United States Design Patent** (10) **Patent No.:** **US D1,000,915 S**
(45) **Date of Patent:** **** Oct. 10, 2023**

(54) **KNIFE HOLDER**

(71) Applicant: **Xiaoping Wang**, Guangdong (CN)

(72) Inventor: **Xiaoping Wang**, Guangdong (CN)

(**) Term: **15 Years**

(21) Appl. No.: **29/782,699**

(22) Filed: **May 8, 2021**

(51) LOC (14) Cl. **07-99**

(52) U.S. Cl.

USPC **D7/697; D7/693**

(58) **Field of Classification Search**

(57) **CLAIM**

The ornamental design for a knife holder, as shown and described.

DESCRIPTION

FIG. 1 is a front and top perspective view of a knife holder showing my new design;

FIG. 2 is a front and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

1 Claim, 8 Drawing Sheets
